UNITED STATES PATENT OFFICE.

CHARLES BOOZ, OF BUFFALO, NEW YORK, ASSIGNOR, BY MESNE ASSIGNMENTS, TO GEORGE K. BIRGE, OF SAME PLACE.

DESIGN FOR WALL-PAPER.

SPECIFICATION forming part of Design No. 24,843, dated November 5, 1895.

Application filed October 3, 1895. Serial No. 564,551. Term of patent 3½ years.

To all whom it may concern:

Be it known that I, CHARLES BOOZ, a citizen of the United States, residing at Buffalo, in the county of Erie and State of New York, have invented and produced a new and original Design for Wall-Paper, of which the following is a specification, reference being had to the accompanying drawing, showing a part thereof.

The design consists of an arrangement of perpendicular stripes or bands containing oval medallion ornaments suspended by bows of ribbon, with sprays of flowers and leaves and crossed torch-shaped ornaments tied by bows of ribbon arranged alternately with said medallion ornaments, said stripes or bands being separated by ornamental stripes or bands with small flowers and leaves running through the center of the ornamental stripes or bands, and plain stripes or bands with a small vine twining around a light ribbon running through the center of the plain stripes, as represented in the accompanying drawing.

The border of the design is formed of crossed torch-shaped ornaments suspended by bows of ribbon, with oval medallion ornaments placed between said torch-shaped ornaments and connected by said ribbons, with festoons of flowers and leaves connecting said torch-shaped ornaments and medallion ornaments, as shown in the drawing. An ornamental band forms the bottom of the border, as shown.

What I claim is—

1. The design for wall paper herein shown and described.
2. In the design for wall paper, the border herein shown and described.

Witness my hand this 27th day of September, 1895.

CHARLES BOOZ.
